UNITED STATES PATENT OFFICE.

HERBERT HASTINGS, OF BRIGHTON, NEW YORK.

PRESSURE-GAGE.

1,399,117.

Specification of Letters Patent.

Patented Dec. 6, 1921.

Application filed June 3, 1919. Serial No. 301,472.

To all whom it may concern:

Be it known that I, HERBERT HASTINGS, a citizen of the United States, residing at Brighton, in the county of Monroe and State 5 of New York, have invented new and useful Improvements in Pressure-Gages, of which the following is a specification.

My invention relates to pressure gages such as are commonly used in connection 10 with the oiling systems of gasolene engines to show the pressure of the oil in the system.

The objects of my invention are: To provide a direct reading, dial indicating gage which will withstand a high overload with- 15 out interfering with the subsequent operation and accuracy of the instrument. To provide an instrument of the kind with the minimum of joints in the pressure fluid chamber. To provide a gage movement 20 with a minimum number of parts free from screws, pins, rivets, nuts or parts apt to become loose or fail to perform their intended function. To provide means for clamping the gage to a panel or plate. To 25 provide a gage which will accomplish the above objects and in addition be adaptable to economical manufacture on a high production basis.

I attain these objects by the mechanism 30 and means shown in the accompanying drawings in which—

Figure 1. is a partial sectional view of a device embodying my invention, taken on the line 1—1 of Fig. 3.

Fig. 2 is a sectional view on the line 2—2 of Fig. 1 with the dial removed.

Fig. 3. is a front or face view of the assembled device less the means for clamping it to the panel.

Fig. 4. is an edgewise view of the movement plate looking in the direction of the arrows and normal to the line 2—2 of Fig. 2.

Fig. 5. is an enlarged partial sectional view on the line 5—5 of the case and on the broken line 5—5—5 of the plate Fig. 2 showing a corrugated diaphragm and diaphragm support.

Fig. 6. is a view of the helical indicator stem 6 shown in Fig. 5 taken on a plane 50 at right angles thereto.

Fig. 7. is a partial sectional view on the

line 7—7 of Fig. 8, showing means for clamping the gage to a panel.

Fig. 8. is a view partially in section on the line 8—8 of Fig. 7. 55

Like reference characters refer to like parts throughout the different views.

1 is a case provided with a flange 1^a, a dial seat 1^b, a bottom 1^c, a diaphragm housing 1^d and a threaded portion 1^e adapted to receive a tube connection and diametrically opposite projections 1^f.

2 is a flexible diaphragm provided with a frictional or wearing block 2^a.

3 is a diaphragm stop plate and is provided with a perforation 3^a, a stop surface 3^b adapted to limit the movement of the block 2^a in one direction and the surface of the stop plate 3 contiguous to the diaphragm is shaped to conform to the shape of the diaphragm. 70

4 is a movement plate provided with an upturned, forked projection with a fulcrum edge or bearing 4^a, an up-turned forked guide 4^b, an up-turned L-shaped bearing 75 projection 4^c provided with a perforation 4^d, a second perforation 4^e in alignment therewith, a projection 4^f at the outer extremity of 4^c and on the vertical center line of the instrument, two up-turned spring retaining clips 4^g and an up-turned spring controller 4^h.

5 is a motion transfer and multiplying lever provided with a notched fulcrum bearing 5^a, a spring retaining notch 5^b, a diaphragm contact projection 5^c, a stop projection 5^d, a flexible portion 5^e and a portion 5^f adapted to contact with the helix 6^c. 85

6 is a helical indicator stem provided with a short bearing projection or trunnion 6^a, 90 a longer bearing projection 6^b and a helical portion 6^c.

7 is a dial provided with suitable graduations 7^a and a notched perforation 7^b shown dotted in Fig. 3. 95

8 is an indicator provided with a perforation 8^a.

9 is a spacing ring.

10 is a glass or transparent disk.

11 is a retaining ring.

12 is a lever retaining and pressure resisting spring.

100

13 is a clamping yoke provided with depressions 13^a, with screw receiving perforation 13^b, with a circular central perforation 13^c, with right angle lips 13^d and internal notches 13^e.

5 14 are screws provided with nuts 15.

16 is an instrument panel or plate and is perforated at 16^a.

10 The assembly and functions of the above parts may be described thus.

The diaphragm 2 with the wearing block 2^a attached thereto is assembled on the reinforcing plate 3 by turning the outer edge of the former back over the edge of the plate 15 and closing the edge down against the back of the plate. When thus assembled the diaphragm and plate are inserted in the housing 1^d of the case 1 and soldered as at s. This solder serves to anchor the diaphragm and

20 plate to the case and also to seal against leakage between the diaphragm and the case. It will thus be seen that as fluid pressure is applied to the left hand side (Fig. 1) of the diaphragm the diaphragm flexes to the right

25 giving a relative movement of the wearing block in that direction and as the pressure increases the movement continues until the wearing block contacts with the back of the stop plate at 3^b and coincident therewith the free surface of the diaphragm also contacts with the corresponding surface of the stop plate and any further pressure applied to the diaphragm is transmitted to and carried by the latter plate without strain to or dis-

30 tortion of the diaphragm and to insure this freedom from distortion the back of the stop plate is made of the same form as the diaphragm at the moment of contact.

The indicator stem 6 is assembled in its 40 bearings on the plate 4 by inserting the end 6^b into the hole 4^d and then springing the end 6^a into the hole 4^e. The multiplying lever 5 is then inserted in the forked guide so that its notch 5^a rests on the edge 4^a of the movement plate, the intermediate portion 45 of the lever is free to move in the forked guide 4^b, the outer end 5^c of the lever is brought into contact with one side of the spiral under pressure exerted by the flexible or spring

50 portion 5^d of the lever and this spring action operates to keep the lever in close contact with the helix so as to prevent any lost motion between the latter and the lever, the notch 5^b receives the spring 12 which exerts

55 pressure on the lever in a direction to keep the notch 5^a on its seat 4^a at the same time keeping the projection 5^c of the lever in contact with the wearing block 2^a on the dia-

60 phragm, the pressure exerted by the spring 65 on the lever thus determining to an extent, the pressure required on the diaphragm to move the lever a predetermined amount. It will thus be seen that the motion of the dia-

phragm is transmitted to the lever 5 and

lever at the points of contact with the spiral is increased several fold and that the end of the lever thus brushing along the side of the spiral gives the latter an increased angle of oscillation proportional to its helical angle. 70 Thus the indicator 8 which is secured to the end of the indicator stem 6^b has a transverse movement at its free end many fold greater than the movement of the diaphragm.

The spring 12 Figs. 2 and 4 is held in 75 place on the movement plate 4 between the clips 4^c and the face of the plate and in such a position that the free end of the spring beyond one of the clips passes under the spring controller 4^b and the bending of this 80 controller in one direction or the other as shown by dotted lines Fig. 2, regulates the action of the spring by varying the effective free length thereof.

The movement plate 4 is secured inside the 85 case by spot-welding or otherwise attaching it to the bottom thereof.

The dial is inserted in the case underneath the indicator 8, and rests on the shoulder or dial seat 1^b in such a position that the center 90 of the circular portion of the notched perforation 7^b coincides with the center of the indicator stem 6 and the narrow portion of the perforation engages the projection 4^c thus locating the dial in a predetermined 95 angular position.

On top of the dial around the outer edge is a spacing ring 9, on top of this ring is a glass or transparent disk 10 and on top of the latter is a retaining ring 11 which fits 100 tightly within the case and holds the glass, spacing ring and dial firmly in their assembled positions.

In Fig. 7, one of these instruments is shown as attached to an instrument panel 16. 105 The panel is perforated as at 16^a to allow the body of the case 1 to be inserted therein so that the flange 1^a bears against the face of the panel 16. Near the inner end of the body of the case are projections 1^f and 110 engaging these projections is a plate or yoke 13 which is slipped over the projections 1^f by bringing the notches 13^b, which are slightly larger than the projections, into alignment therewith, and after passing over 115 the projections turning the yoke so that the projections 1^f occupy the depressions 13^a in the yoke. The screws 14 are then turned 120 up tight against the back of the panel thus clamping the gage in position. The lips 13^c are provided to keep the nuts 15 from turning and the depressions 13^a are provided to prevent the gage from turning in the yoke when the projections 1^f are held in these depressions.

125 I claim as new and desire to secure by Letters Patent—

1. In a pressure indicating device, a case provided with a pressure chamber, a flexible diaphragm closing one end of said chamber, 130

- an indicator stem journaled in parts of the device and provided with a helix and an indicator, a lever pivotally supported in parts of the device and contacting with the 5 diaphragm and adapted to oscillate the helix, said lever being non-flexible in the direction of its motion but provided with a portion flexible in a plane perpendicular thereto between its support and the helix. 10 2. In a pressure indicating device, a fluid pressure chamber, a flexible diaphragm provided with a reinforced center sealed in one end of said chamber, a rigid plate adapted to continuously support one side of the dia- 15 phragm and its reinforced center, an indicator stem comprising a flat ribbon twisted into a helix and pivotally supported in parts of the device, and provided with an indicator, a lever contacting with the diaphragm 20 and helix and fulcrumed on a part of the device and provided with a flexible portion adapted to maintain a uniform pressure of contact between the lever and the helix, a dial traversed by the indicator and a trans- 25 parent protecting cover for said dial and indicator. 3. In a pressure gage, a case provided with a pressure chamber, a flexible dia- 30 phragm, a stop plate secured to the outer edge of the diaphragm and to the case at one end of the chamber and adapted to uniformly support said diaphragm against distortion under excess strain, a pointer stem provided with a pointer mounted to rotate 35 within the case and means co-acting with the diaphragm and stem to rotate said stem. 4. In a pressure gage, a cylindrical case provided with a fluid pressure chamber, a seat for a movement plate, and a support for 40 a dial; a flexible diaphragm sealed near one end of said chamber, a movement plate secured to said seat and provided with an upturned edge to serve as a fulcrum and an upturned fork to serve as a guide for a lever 45 and provided with means for oscillatably supporting a pointed stem near each end thereof; a lever adapted to oscillate on said fulcrum, a pointer stem operated by said lever to oscillate in said means, a pointer 50 mounted on said stem and a dial mounted on the dial support. 5. In a pressure gage, a case provided with a pressure chamber, a spring dia- 55 phragm closing one end of said chamber, a revolute stem provided with a helix and a pointer, a pivoted lever adapted to engage said diaphragm and helix non-flexible in the direction of its motion but flexible in a plane at right angles thereto, a plate adapted 60 to support said stem and lever, a spring for holding said lever in contact with the dia- phragm and in its support on said plate, said lever adapted to maintain uniform 65 contact with the helix through the flexibil- 6. In a pressure gage, a case provided with a fluid pressure chamber, a member closing one end of said chamber mounted therein flexibly responsive to a change of pressure within the chamber, a stop plate 70 adapted to retain said member in said chamber and to uniformly support it against excessive deflection, a helical indicator stem mounted to oscillate within the case, a flexi- 75 ble lever contacting with said member through the influence of a spring and contacting with the helical stem through the influence of the flexible portion of the lever, a pointer mounted on the stem and a dial supported at one side of the pointer. 80 7. In a pressure gage, a case provided with a fluid pressure chamber, a diaphragm flexibly responsive to change of pressure mounted to close one end of said chamber, a stop member adapted to hold said dia- 85 phragm in said chamber and adapted to limit the flex of the diaphragm, a dial provided with a graduated scale mounted within the case, a pointer adapted to traverse said graduations and means for transmitting 90 the motion of the diaphragm to amplified motion of the pointer. 8. In a pressure gage, a case provided with a pressure chamber, a flexible dia- 95 phragm closing one end of said chamber, a stop member adapted to hold said dia- phragm in position in the chamber and to stop it against excessive flexure, a pointer stem and pointer, a rocking member, means for supporting said stem and rocking mem- 100 ber so that said rocking member co-acts with said diaphragm and said stem to rotate the stem and a spring acting on said rock- 105 ing member to keep it in contact with said diaphragm. 9. In a pressure gage, a case provided with a pressure chamber, a spring diaphragm held in one end of said chamber by a stop plate which plate is adapted to limit the movement of said diaphragm, a pointer stem provided with a helix and a pointer, a lever adapted to contact with said dia- 110 phragm and helix to oscillate the latter, a member adapted to pivotally support said stem and lever, a spring adapted to keep said lever in contact with the diaphragm and on its pivot, said lever being made flexible in a plane perpendicular to its motion adapted to maintain yielding but constant contact with said helix. 115 10. In a pressure gage, a pressure cham- 120 ber a portion of which is formed by a mem- ber flexibly responsive to change of pres- 125 sure, means for limiting the flex of the mem- ber continuously from center to circumfer- ence, a lever contacting with said member, a spring acting upon the lever to cause it to press against the member, means for reg- 130 ularizing the action of the spring and a pointer stem with pointer thereon adapted

to be actuated by the lever in proportion to the movement of the flexible member.

11. In an instrument of the class described in combination, a supporting panel 5 provided with a perforation, an instrument case provided with a body portion with spaced shouldered projections thereon adapted to pass through said perforation and also provided with a flanged portion 10 adapted to engage the panel around said perforation, a yoke provided with a notched perforation adapted to permit the insertion of the body and projections and to engage back of the shouldered projections when inserted and means coacting between the yoke 15 and the panel for clamping the case thereto.

12. In an instrument of the class described, the combination of, an instrument panel provided with an opening, an instrument case adapted to be mounted in said opening and provided with projections spaced from one side of the panel and with a flange contacting with the other side thereof, a yoke with a notched perforation 25 adapted to be assembled over the projections on the case and provided with depressions adapted to engage back of the projections to prevent rotation of the case within the yoke and means coacting between the 30 panel and yoke for clamping the case in position thereon.

13. In an instrument of the class described, the combination of, an incasement comprising a cylindrical body portion and an annular flange the body portion being provided with shouldered projections, a panel provided with a perforation in which the incasement is adapted to be supported and means coacting with the shouldered 40 projections, the panel and the flange for securing the incasement in position on the panel.

14. In a pressure indicator, the combination of a movement plate provided with 45 slotted guides adapted to fulcrum and support a lever and provided with pivot bearings for a helix, a lever fulcrumed in one of said guides and swinging in the other guide, said lever being made thick and stiff between the guides and being held in line 50

thereby, said lever being reduced in thickness beyond the guides to make it thin and flexible, a helix against which the side of the outer end of the lever is yieldingly held by the guides and the flexible part of the 55 lever, said helix being supported in said pivot bearings.

15. In a pressure indicator, the combination of a movement plate provided with guides for a lever and bearings for a helix, 60 a lever adapted to swing in said guides, said lever being made thick and stiff between the guides and being held in line thereby, said lever being reduced in thickness beyond the guides to make it thin and flexible laterally 65 of the guides, a helix pivoted in said bearings and against which the side of the lever at the outer end is yieldingly held by the guides and the flexible part of the lever.

16. In a pressure indicator, the combination of a case provided with a pressure chamber, a flexible diaphragm mounted therein, a stop plate also mounted therein, the periphery of the stop plate being in contact with the periphery of the diaphragm, the 70 stop plate toward the center slightly diverging from the diaphragm in normal position, the diaphragm making contact therewith under pressure, and means for securing said diaphragm and plate in said chamber. 80

17. In a pressure indicator, the combination of a case provided with a pressure chamber, a flexible diaphragm mounted therein, a stop plate also mounted therein, the periphery of the stop plate being in 85 contact with the periphery of the diaphragm, the stop plate toward the center slightly diverging from the diaphragm in normal position, the diaphragm making contact therewith under pressure, the stop plate having an opening in the center thereof, a wearing block on the diaphragm making contact with the stop plate around the opening, and means for securing said diaphragm and plate in said chamber. 90
